Attorney

UNITED STATES PATENT OFFICE.

JOHN HENRY LEPPER, OF MASON CITY, IOWA.

ELECTRICAL VAPORIZER.

1,222,425.

Specification of Letters Patent. Patented Apr. 10, 1917.

Application filed June 27, 1916. Serial No. 106,178.

To all whom it may concern:

Be it known that I, JOHN HENRY LEPPER, a citizen of the United States, residing at Mason City, in the county of Cerro Gordo and State of Iowa, have invented certain new and useful Improvements in Electrical Vaporizers; and I do hereby declare the following to be a full, clear, and exact description of the invention, such as will enable others skilled in the art to which it appertains to make and use the same.

This invention relates to an electrical vaporizer, and is more particularly designed for use in connection with automobile engines.

One of the objects of this invention is the provision of a vaporizing device adapted to be mounted in the wall of the intake manifold of the engine for efficiently vaporizing the explosive mixture in its passage through the intake manifold.

Another object of this invention is the provision of a vaporizer having the joints between its parts thoroughly sealed with asbestos washers.

A further object of this invention is the provision of an electrical vaporizer consisting of few parts and which can be manufactured and sold upon the market at a nominal cost.

These and other objects and advantages will more fully appear as the nature of the invention is more clearly understood from the following specification, the subject matter of the claim, and the views illustrated in the accompanying drawings, in which,

Figure 1 is a side elevation of the intake manifold of an internal combustion engine, the leg thereof being shown as broken away, showing the invention in applied operative position.

Fig. 2 is a vertical longitudinal sectional view through the vaporizer and a portion of the adjacent wall of the leg of the intake manifold.

Referring to the drawings, wherein similar reference characters denote corresponding parts throughout the several views, 1 denotes the intake manifold of an internal combustion engine and 2 the leg of the intake manifold leading to the carburetor, the leg 2 having formed in a wall thereof the internally screwthreaded opening 3.

Within the screwthreaded opening 3 of the leg 2 of the intake manifold 1 is mounted the externally screwthreaded end 4 of the

plug 5, formed with the centrally disposed exterior annular shoulder 6, and being provided at its outer end with the head 7 of hexagonal shape adapted to receive a suitable wrench for inserting or removing the plug 5 with respect to the screwthreaded opening 3 of the intake manifold. Within the plug 5 is formed the enlarged bore 8 extending for the greater portion of the distance therethrough and communicating with the smaller bore 9 extending the remaining distance through the plug 5, and between the enlarged bore 8 and the smaller bore 9 is formed the shoulder 10, the inner portion of the enlarged bore 8, however, being provided with the internally threaded portion 11 adjacent its outer end.

Projecting through the plug 5 is the inner portion of the insulating core 12, formed of porcelain, mica, or other suitable insulating material, and having its outer portion projecting outwardly beyond the outer end of the plug 5. The insulating core 12 is provided with the reduced inner end 13, between which and the main body portion of the insulating core 12 is formed the enlarged annular head 14, and formed longitudinally through the reduced end 13 of the insulating core 12 and projecting for a distance into the head 14 is the enlarged bore 15, and extending from the bore 15 and communicating therewith to the outer end of the body portion of the core 12 is the smaller bore 16. The insulating core 12 has a portion of its main body portion and its head 14 positioned within the enlarged bore 8 of the plug 5 with the periphery of the head 14 contacting with the inner smooth wall of the enlarged bore 8 of the plug 5, while the reduced inner end 13 of the insulating core 12 is snugly seated within the smaller bore 9 of the plug 5, the inner end of the reduced end 13 of the insulating core 12 and the inner end of the plug 5 preferably lying flush with each other, or in other words in the same plane.

For securely mounting the insulating core 12 in operative position within the plug 5, the exteriorly threaded locking ring 17 is provided and has formed upon its outer end the head 18, preferably hexagonal and adapted to receive any suitable form of wrench for screwing the locking ring 17 within the threaded portion 11 of the plug 5. The locking ring 17 surrounds and snugly embraces the outer surfaces of the main body

portion of the insulating core 12 within the plug 5 and for a distance just outside of the plug, whereby when the locking ring 17 is screwed home within the plug 5 the inner end of the locking ring 17 engages the front shoulder of the head 14 of the insulating core 12 and forces the rear shoulder of the head 14 against the shoulder 10 within the plug 5. There is, however, interposed between the shoulder 6 of the plug 5 and the adjacent wall of the leg 2 of the intake manifold, the rear shoulder of the head 14 and the shoulder 10 within the plug 5, and between the inner end of the locking ring 17 and the front shoulder upon the head 14 the gaskets or packing rings 19, 20 and 21 respectively to provide tight joints therebetween.

Projecting through the insulating core 12 and extending for a distance beyond each end thereof is the metal core 22, provided substantially centrally thereof with the annular enlargement 23 which is positioned within the larger bore 15 of the core 12 and which seats against the shoulder 24 formed between the enlarged bore 15 and the smaller bore 16 of the core 12, and upon the inner end of the metal core 22 which projects through the bore 15 of the core 12 and for a distance within the leg 2 of the intake manifold, is formed the head 25 provided in one side with the socket 26 in which is seated the end 27 of the heating coil 28 which surrounds that portion of the metal core 22 between the head 25 and the inner end of the plug 5, and formed within the face of the inner end of the plug is the socket 29 in which is seated the opposite end 30 of the heating coil 28. The metal core 22 is provided with the screw threaded outer end 31 upon which is threaded the cap 32 which also embraces the outer end of the insulating core 12, and interposed between the enlargement 23 of the core 22 and the shoulder 24 of the core 12 is the gasket or packing ring 33, and there is also interposed between the cap 32 and the outer end of the insulating core 12 another gasket or packing ring 34, the gaskets 33 and 34 preventing any leakage through the bore 16 of the core 12, and when the cap 32 is screwed home upon the threaded end 31 of the metal core 22 the enlargement 23 binds against the gasket 33 and cap 32 against the gasket 34, whereby the metal core 22 is securely and operatively mounted within and through the insulating core 12 and also maintains the heating coil 28 in operative position within the leg 2 of the intake manifold.

For energizing the heating coil 28 for vaporizing the explosive mixture in its passage through the leg 2 of the intake manifold, the outer end of the metal core 22 is connected with any suitable source of electrical supply, controlled by a suitable switch,

by the conducting wire 35 secured around the end of the metal core 22 and retained in operative position through the medium of the binding screw 36 also screwthreaded upon the threaded end 31 of the metal core 22 and binds against the adjacent face of the cap 32.

Preferably the heating coil 28 is energized by the current passing through the conducting wire 35, the metal core 22, the head 25 thereof, and through the heating coil 28 from its end 27 to its end 30, whereby the circuit is returned through the inner end 4 of the plug 5 the adjacent wall of the leg 2 of the intake manifold and thence returned through the plug 37 through the return wire 38 back to the source of electrical supply, the end of the wire 38 being secured to the plug 37 by the binding screw 39, the plug 37 is either threaded into a wall of the leg 2 of the intake manifold or otherwise secured thereon as at 40, however, the current may be conveyed back to the source of electrical supply through any part of the engine or the engine frame if desired.

The insulating core may be formed of any suitable and desirable insulating material and the metallic parts of the device may be formed of any suitable and desirable metal or metals, and while the gaskets or packing rings 19, 20, 21, 33 and 34, which I employ, may be formed of any suitable packing material I preferably form these gaskets or packing rings of asbestos, which not only forms an efficient packing ring but minimizes heat radiation through the device.

I desire it to be understood that, while my invention is primarily designed for an electrical vaporizer to be mounted through a wall of the leg of the intake manifold employed in the construction of the internal combustion engines used upon automobiles, the invention is equally adaptable to be applied through a wall of the intake manifold proper, or through a wall of the intake pipe of any other form of internal combustion engine, and, furthermore, the device constituting my invention may be applied to the oil well of a carburetor for heating the fluid therein, or the same may be used as a heater for other purposes than those above set forth and wherever the same is adaptable.

Having described my invention, what I claim as new and desire to secure by Letters Patent, is:

A vaporizing device adapted to be positioned in an opening in the manifold of an engine, said vaporizer including a plug, an insulating core having one of its ends extending into the plug, said core having a central bore, a metallic core positioned within the central bore whereby its free end extends beyond the end of the plug, an enlarged head supported on one end of the metallic core, a heating coil surrounding the metallic core and supported in spaced rela-

tion therewith, one end of said heating coil being embedded in the enlarged head, the opposite end of the coil being embedded in the end of the plug, whereby the entire surface of the heating coil is exposed to the atmosphere of the engine-manifold.

5 In testimony whereof I have signed my

name to this specification in the presence of two subscribing witnesses.

JOHN HENRY LEPPER.
